BOX

Robert Archer Muller, Wellesley, Mass., assignor to No Nail Cases Proprietary, Limited, Melbourne, Victoria, Australia, a company of Victoria, Australia (1928)

Application July 21, 1939, Serial No. 285,707

1 Claim. (Cl. 217—12)

This invention relates to boxes and packing cases of the type designed fundamentally for use in the shipment of merchandise.

Because such use is purely temporary, and the competition in this line is extremely keen, the commercial use of any given type of box depends very largely on the price for which that box can be sold. Furthermore, because the function of such a box or packing case is to protect the merchandise shipped in it, and it must necessarily be expected that it will be subjected to very rough usage, it is also essential that such a box shall have the strength, stiffness and rigidity to enable it to successfully withstand such usage.

A further requirement, or at least a highly desirable characteristic, of packing cases of this type is that they shall be capable of assembly in or closely adjacent to the plant where they are to be used so that they can be shipped from the point of manufacture to the plant in a knocked down or collapsed condition. In addition, the nature of the box must be such that its assembly will not require any great degree of skill.

With a view to meeting these conditions it has been proposed to make boxes with the bottom, side, and usually the top panels nailed or otherwise secured at their opposite edges to two metal edge binding and hinging strips. These strips are so mitered that such a box blank can readily be folded into a hollow rectangular form. Two end pieces of suitable dimensions can then be set into the opposite ends of this hollow structure and secured to the side and bottom pieces.

While this type of box has been shown in the patented art for many years, it has never gone into commercial use in this country, so far as I have been able to learn. In European countries, where wood is more expensive and the necessity for economy in using it is more compelling than in this country, much attention has been given to this type of box construction. Even in those countries, however, it has become commercial to only a very limited degree, and then only in the kind of box in which the edge binding and hinging strips are provided with integral teeth which are forced through the margins of the panels and clinched.

In attempting to introduce this same box into this country it was found that it could only be used for light loads, such as are handled here in corrugated fiber cartons. They are not strong enough for heavier loads and are too expensive to compete with the corrugated fiber cartons. If, however, the expense of manufacture of this box

could be reduced to reasonable limits, then it would be a valuable addition to the containers already used in this country and abroad, and it would be particularly useful in the shipment of merchandise which cannot be handled in corrugated fiber cartons. This class of merchandise includes such articles as bearings, bolts, and other small hardware parts.

Such a reduction in expense of manufacture of this type of box, however, presents serious problems. As above stated, the only form of this box which has been at all successful has been that in which the edge binding and hinging strips are provided with integral teeth which are forced through the margins of the box panels and clinched. This construction has the advantage of lending itself to manufacture with the aid of automatic machinery and it avoids the necessity for handling independent fasteners in securing the binding strips to the panels. In other words, the use of nails, rivets, staples and screws to fasten these strips to the panels has not proved successful, partly because of the slow speed at which these operations must be performed and partly, also, because of erratic or unsatisfactory clinching of the fasteners on the inside of the box. These steps must be controlled accurately in order to produce a smooth interior and in some cases, also, to give the necessary strength. Moreover, any type of fastening which requires the preliminary formation of holes to receive it, has proved impractical for this particular use.

On the other hand, a practical disadvantage of the edge binding strip equipped with integral teeth is that the composition and thickness or gauge of the strip cannot be selected merely to suit the requirements of the box, but must be determined primarily by the requirements of the teeth. That is, the metal composition must be of such a nature that the teeth will have the necessary stiffness and rigidity to stand up during the process of pressing them through the margins of the panels, together with that ductility or pliability required for good clinching. These conditions usually compel the use of a strip material of a harder composition and considerably heavier gauge than is necessary merely to suit the requirements of the box.

A further objection to this type of box is that the teeth mutilate the material of the panels to a very considerable degree and, partly in consequence of this fact, the box lacks the stiffness and rigidity which is absolutely necessary in using it for the shipment of metal parts. It has a tendency to rattle or "weave" which is highly ob-

jectionable for any purpose except extremely light loads.

The present invention deals with the problems presented by these considerations. It aims to device a box of the metal bound type above referred to and having the advantages of that type of box which will, nevertheless, avoid its shortcomings and objectionable features.

In the accompanying drawings which show a preferred embodiment of my invention,

Figure 1 is a perspective view of the box when closed and sealed;

Fig. 2 is a perspective view of a portion of the box with the top or cover raised;

Fig. 3 is a perspective view of one corner of the box showing a slightly different form of edge binding strip;

Fig. 4 is a plan view of a box blank which also is of novel construction;

Fig. 5 is a plan view of one of the end panels;

Fig. 6 is a vertical, sectional view approximately on the line 6—6, Fig. 1; and

Fig. 7 is a sectional view through a portion of the box beside one of the wire stitches.

Referring first to Fig. 4, the box blank there shown comprises four panels, A, B, C and D, respectively, the panels B and D being intended to form the sides of the box, the panel C the bottom, and that shown at A the top or lid. These panels are all secured together in alignment with each other, approximately edge to edge but spaced slightly apart, by metal edge binding strips 2—2. Each of these strips is of angular form in cross-section, as better shown in Figs. 1 and 2, and comprises a continuous flange *a* designed to extend circumferentially around the box and another flange *b*, at right angles to the flange *a*, and notched or mitered to facilitate folding at the edges of the box. Preferably the latter flange has a bead formed in it, as indicated at *c*, Figs. 1, 2 and 6. This edge binding and hinging strip is similar to those used heretofore except that the flange *a* is made continuous and is not interrupted by the formation of teeth in it. Consequently, it is stronger for given dimensions than otherwise would be the case.

Instead of using teeth integral with the strips 2—2 to secure them to the end margins of the panels, they are fastened by so-called "wire stitches" 3. The attachment of these strips to the panels can be performed very rapidly in a machine equipped with wire stitching heads, such for example, as that known commercially as the Bliss Head. These mechanisms are designed to draw wire from supply coils, to cut off suitable lengths required for individual stitches, to form them into a U-shape, and drive them into the work, the entire operation requiring only a fraction of a second. Consequently, this attaching operation can be performed while the blanks are moved continuously through the machine. Also, the legs of these fasteners are cut off practically square and they are so guided during the driving of them that they punch their own holes, even through the metal strips 2, which usually are made of cold rolled steel, and the panels which may, for example, be made of plywood.

Preferably the stitches are driven lengthwise of the strips 2—2 and the panels are so positioned on them that the grain of the inner and outer plies runs transversely to the metal strips. Consequently, when the ends of these stitches are clinched toward each other, as shown in Fig. 7, each one of these fasteners grasps a bundle of fibers extending transversely through it and

clamps the flat flange *a* securely to the panel. The clinching of the ends of these stitches can be accurately controlled and the extreme ends or tips are embedded in a ply of the panels so that a relatively smooth interior surface is left. It should also be observed that this method of fastening does not materially weaken either the metal flanges *a* or the margins of the plywood panels through which the fasteners are driven because the holes made in these parts are only substantially as large as the cross-sectional dimensions of the wire, and for ordinary purposes a steel wire of, say, only twenty-thousandths to thirty-thousandths of an inch in diameter is required.

Either simultaneously with the stitching of the edge binding and hinging strips 2—2 to the panels, or at any other convenient time, a metal reinforcing strap 4, Figs. 1 and 4, is also secured to them by wire stitches. This strap lies between the edge binding strips and extends parallel to them. In larger boxes it often is desirable to use more than one of these reinforcing straps. While the number of fasteners used in securing each strap in place may be varied, a good arrangement is to stitch the strap to the side panels B and D closely to the upper and lower edges of them, to the bottom panels C at the middle and also near its opposite edges, and to leave it unattached to the top panel A.

In the particular box structure shown, the panels above referred to do not abut against the flanges *b* of the edge binding strips 2—2 but are so positioned on the flanges *a* that a space is left between the edge or end faces of the panels and the flanges *b*. Such spaces are shown at *d* in Figs. 2 and 4 and they are made wide enough to receive comfortably the edges of the end panels E and F, Figs. 2, 5 and 6. These panels also may consist of the same material as those of which the other panels are made, and they preferably are equipped with metal lugs 7, either provided with teeth punched from them, as shown in Figs. 1 and 6, or, more preferably, wire stitched to the outer faces of the end panels.

In assembling one of these boxes, the blank shown in Fig. 4 is folded at the mitered notches or cut-outs formed in the flanges *b* of the metal strips 2—2 to bring the side panels B and D into right angle relationship to the bottom panel C, the top panel or lid A being left up. The end panels E and F are then slid into the channels *d* provided at the opposite ends of the box, as above described, and the lugs 7 are inserted through slots 8 provided in the strips 2—2 to receive them. Those lugs opposite the side and bottom panels then are folded over, as shown in Fig. 1, where they serve to hold this whole assembly in its box-like or open condition during the filling or packing of the box. It should be observed that at this time the reinforcing strap 4 holds the bottom panel C suspended from the side panels. This is particularly important when the boxes are supported by their ends only on rails or horses during the filling or packing operation, both because it gives added strength to the box and also for the reason that it prevents bulging at the bottom of the box and holds the opposing edges of adjoining panels in correct relationship to each other.

After the box has been filled, it is closed by forcing the lid down in to the position shown in Fig. 1, and it is locked there by forcing the slotted ends 10 of the strips over the tabs or tongues 9 at the opposite ends of them, and then folding these tongues downwardly, as illustrated in Fig. 1.

The lugs 7 at the upper edges of the end panels also are inserted through the slots 8 during the closing of the lid and they likewise are folded over, as shown in Fig. 1. Thereafter the end portions of the reinforcing strap 4 are overlapped, one upon the other, upon the lid A and are tightened by means of a tool commonly used for this purpose in box strapping operations, and then are secured permanently together in any convenient way as, for example, by the so-called Acme Seal, as shown at 5 in Fig. 1. This seal is crimped into the edges of the overlapped portions of the straps and secures them firmly together as is well understood by those skilled in the use of box strapping equipment.

Because the strap 4 is fastened to the side panels closely adjacent to their upper edges and preferably, also, to this and the bottom panel at other points, any danger of overtightening the box to such a degree as to distort it materially is avoided. This is likely to occur with a loose strap because of the tendency of the pull exerted on it to make the box assume a circular form.

A box of this construction, even when empty, is immensely stronger than those made by the methods described in the introductory portion of this specification. In fact, merely the addition of the reinforcing strap 4, in the manner here shown, to the box made with the edge binding and hinging strips equipped with integral teeth, adds in an astonishing degree to the strength and rigidity of that box. It materially reduces its tendency to rack and weave and obviates its objectionable bulging and warping during filling. A box made of even relatively thin plywood in the manner shown in the drawings possesses surprising strength, rigidity and stability. In part, this is due to the fact that the strength of the metal members is used very efficiently, but much of the tendency to weave or rack is eliminated by the more secure fastening of the edge binding strips 2-2 to the margins of the side, bottom and top panels and the elimination of any weakening of the material of these panels at the points of attachment. A further and important factor is the secure binding of those portions of the metal flanges *a* against the edge faces of the end panels E and F. This is accomplished in some degree by the lugs 7 but in a large measure also by the tightening of the reinforcing strap 4, the lugs being provided primarily for the purpose of holding the sides and bottom of the box to the end pieces during the filling operation. The fact that this strap is secured to the side and bottom panels also contributes to added resistance to racking.

With this construction it is entirely practical to provide the flanges *a* of the edge binding and hinging strips with longitudinal ribs which serve to stiffen these parts. Such a construction is shown in Fig. 3. The wire stitches used in securing the edge binding strips and the reinforcing straps to the box panels are not like the common staples but, on the contrary, are relatively long, the distance between their legs being such that they bridge a very considerable width of plywood stock. It is partly because of

this fact that they lock the metal straps and strips securely to the panels. At the same time they avoid the mutilation of the wood and often, also, of the metal, which is produced in attempting to use staples of the common form. Also, the fact that the ends of the legs are blunt or square instead of being tapered, as in staples of the usual form, enables these elements to broach their own holes in the metal straps and strips and is likewise of assistance in controlling the clinching of these legs accurately.

A box made in the manner above described can be produced on a commercial scale with less expensive machinery than that required for the other forms of boxes of this general character above referred to. Also, it overcomes the defects in and objectionable characteristics of these prior boxes which appear to have been responsible for their failure to attain commercial success.

At the same time the very important advantage of this type of box that it can be shipped in a knocked-down condition and assembled at the point where it is to be used, packed, closed and sealed, without the necessity for driving fasteners, and without requiring any substantial degree of skill, has been preserved.

Having thus described my invention, what I desire to claim as new is:

- 30 A box comprising a folding elongated one-piece blank including a plurality of panels adapted to form the sides, bottom and top of the box, end members forming the ends of the box, two angle-sectional metal strips secured to opposite edges of the blank for binding and hinging the panels together and for enclosing the end members, each of said strips comprising a body portion and a flange portion extending at substantially right angles to the body portion, the body portion of each of said strips being secured to the outer end edges of said panels and the flange portion being spaced from the end faces of the panels and providing channels at opposite sides of the blank between said flanges and said end faces, said end members extending into said channels and the flange portions contacting the outer face of the adjacent end panel when the box is set up, locking means connected to the outside of said end members between the corners of the box, each of said locking means having a deformable portion extending through a slot in the body portion of the adjacent strip and arranged to be folded outwardly over and against the adjacent flange portion when the box is set up, a metal reinforcing strap between said strips, means for wire stitching said strap to the opposite sides and to the bottom of the box but not to the top thereof, said strap having free end portions adapted to overlap and be secured together above the top, and means connecting the overlapped ends of the strap, said strap coating with the fastening means to support and prevent the bottom and sides of the box from bulging when being loaded and for insuring the top being firmly maintained in position without distorting the box when a tightening force is applied to the strap.
